UNITED STATES PATENT OFFICE.

DAVID H. MOSS, OF NEWARK, NEW JERSEY, ASSIGNOR, BY MESNE ASSIGNMENTS,
TO BRANDES LABORATORIES, INC., OF NEWARK, NEW JERSEY, A CORPORATION
OF NEW JERSEY.

TERMINAL FOR TELEPHONE RECEIVERS.

Application filed February 27, 1925. Serial No. 12,148.

To all whom it may concern:

Be it known that I, DAVID H. Moss, a citizen of the United States, residing at Newark, in the county of Essex and State of New Jersey, have invented a certain new and useful Improvement in Terminals for Telephone Receivers, of which the following is a specification.

My invention relates broadly to telephone headsets and more particularly to a construction of terminal post for telephone receivers.

One of the objects of my invention is to provide a construction of telephone receiver having parts arranged in such manner that the receiver is capable of manufacture on a quantity production basis at relatively low cost.

Another object of my invention is to provide a construction of telephone receiver in which the assembly of the parts is facilitated by the provision of terminal posts having soldering heads projecting interiorly of the telephone receiver with binding posts formed integrally therewith and projecting from the rear of the telephone receiver casing.

Still another object of my invention is to provide a terminal post which may be rigidly secured in the rear of a telephone receiver casing with means for substantially insulating the terminal post from the parts of the telephone receiver mechanism with a lug member projecting from the terminal post interiorly of the receiver to facilitate the soldering of the extremities of the magnet windings to the terminal post during the assembly process.

My invention will be more clearly understood from the following specification by reference to the accompanying drawings, in which:

Figure 1 is a plan view of the interior of a telephone receiver casing with the operating parts partially assembled therein; Fig. 2 shows a cross sectional view of a telephone receiver casing with the terminal posts of my invention secured in the rear of the casing and arranged with the soldering heads mounted adjacent the magnet system for the securing of the magnet windings thereto; Fig. 3 illustrates the several parts which make up the terminal posts of the telephone receiver comprising my invention.

Fig. 4 is a perspective view of the telephone receiver terminal post; Fig. 5 is an enlarged fragmentary plan view showing the relation of the soldering head of the terminal post to one of the electromagnets within the receiver; and Fig. 6 is a fragmentary cross sectional view illustrating the method of rigidly securing the terminal posts within the telephone receiver casing.

Heretofore in the art telephone receivers have had their magnet windings connected to binding posts of ordinary design and which have not been particularly adapted for assembly of the telephone receiver and connection of the magnet windings within the small available space of the telephone receiver casing. A terminal block has often been employed within the telephone receiver, requiring the opening of the telephone receiver cap to permit the insertion of terminals through one side of the telephone receiver casing and the binding of those terminals against the contacts upon the terminal block in order to complete connections between the flexible conductor leading to the telephone receiver casing and the windings of the electromagnets within the receiver. The removal of the caps from the telephone receiver casings after they have passed factory inspection and have been delivered to the customer is undesirable for the reason that it tends to destroy or greatly impair the adjustment of the telephone receiver. By my construction of terminal post I avoid the necessity of removing the cap from the telephone receiver and permit connections to be made from the exterior of the telephone receiver without disturbing the original adjustment of the receiver. The terminal post construction of my invention greatly facilitates the securing of the binding posts in the rear of the telephone receiver casing and at the same time facilitates the assembly of the telephone receiver by permitting the magnet windings to be readily soldered to the binding post terminals as will be hereinafter more fully explained.

Referring more particularly to the drawings, the telephone receiver casing has been indicated by reference character 1. The magnetic angles on which the electromagnetic bobbins 4 and 5 are wound are represented by reference characters 2 and 3.

sented as having laterally extending portions 2 and 3 and upright pole pieces 6 and 7. The laterally extending portions 2 and 3 are apertured at 11, which apertures 5 register with apertures 10, formed in the telephone receiver casing. The terminal post forms a unitary means by which the magnetic angles are rigidly secured within in the telephone receiver casing in proper 10 position and at the same time the binding post rigidly secured with relation to the rear of the telephone receiver casing, the post being substantially insulated from the parts of the telephone receiver mechanism. The 15 binding post comprises an extended shank 12 having an enlarged portion 14 adjacent one end with an extension 9 forming a soldering head projecting therefrom. The enlarged portion 14 may be so shaped at its 20 periphery as to facilitate the gripping of the post and the insertion of the post within the telephone receiver casing, during the assembly process. The soldering head 9, which extends from the enlarged portion 14, has 25 a diameter substantially less than the diameter of the shank 12 and projects upwardly, being formed with a substantially conically shaped head as has been indicated. The enlarged portion 14 does not have both 30 its upper surface and lower surface parallel, but the lower surface is cut at a substantial angle to the axis of the terminal post forming a beveled under head with a surface 15 angularly disposed at substantially 35 60 degrees with respect to the axis of the terminal post 12. The purpose of the angular disposition of the surface 15 is to enable the binding post to be drawn rigidly against and thereby deform an insulated gasket 8 which is substantially out 40 of round at its periphery enabling it to be readily gripped and slipped over the shank 12 during the assembly process. The shank 12 passes through an insulated sleeve 17 45 disposed in the aperture 10 in the rear wall of the telephone receiver casing. An insulated gasket 18 is positioned against the outside surface of the rear wall of the telephone receiver casing 1 and the threaded portion 16 of the shank 12 passes through 50 this gasket permitting nut 19 to be screwed rigidly against gasket 18 drawing the enlarged portion 14 against the insulated gasket 8. The enlarged portion 14 is so shaped 55 at its periphery that a plurality of biting teeth 20 are formed thereon, which teeth bite into the material of gasket 8 thereby rigidly securing the terminal post within the telephone receiver casing. In the assembly 60 process the conductors 21 extending from the magnet bobbins are readily moved against the soldering head 9, flux, solder and heat applied thereto, and a rigid connection secured. The time necessary in 65 making this connection is considerably re-

duced over the time operation heretofore necessary in telephone receiver constructions previously known in the art.

It will be appreciated that the construction of my terminal post greatly facilitates 70 manufacture of telephone receivers on a basis of many thousands per day. In large production programs of this kind individual operators are assigned a particular duty and my terminal post has been designed 75 after a careful study of time operations normally encountered in telephone receiver manufacture. By the construction herein described I have succeeded in both reducing 80 the time required in the assembly of the telephone receiver and in producing a more desirable product.

While I have described my invention in certain particular embodiments, I desire 85 that it be understood that modifications may be made and that I intend no limitations upon the invention other than those imposed by the scope of the appended claims.

What I claim and desire to secure by 90 Letters Patent of United States is as follows:

1. An electromagnetic sound reproducer, comprising in combination a casing, an electromagnetic operating mechanism carried within said casing; a pair of terminal posts projecting through the rear wall of said casing for mechanically securing said electromagnetic operating mechanism in position and electrically completing connections 95 between said electromagnetic operating mechanism and the exterior of said casing, said terminal posts comprising screw-threaded shanks having enlarged irregularly shaped heads adjacent one end thereof 100 with soldering heads extending from said irregularly shaped heads and extending into said casing, insulating means concentrically disposed upon said screw threaded shanks and substantially separating the surfaces of said casing from said terminal posts, and teeth formed on said enlarged heads for distorting the shape of said insulating means whereby said terminal posts are rigidly secured in position with respect 105 to said casing.

2. In an electromagnetic sound reproducer, the combination with a casing of an electromagnetic sound operating mechanism carried within said casing and terminal posts arranged to secure said electromagnetic sound operating mechanism within said casing, said terminal posts each comprising screw threaded shanks, enlarged under-cut heads adjacent one end thereof and soldering heads extending from said enlarged heads interiorly of said casing, said terminal posts being insulatingly supported with respect to the lower wall of said casing with said under-cut enlarged heads 110 serving to prevent rotation of said terminal 115 heads.

- posts with respect to said casing when said posts are secured in position.
3. A terminal post for electromagnetic sound reproducers comprising in combination with a casing, a screw threaded shank, an enlarged head adjacent one end thereof, a soldering head extending from said enlarged head, said enlarged head having an under-cut surface disposed at an angle to the axis of said shank, forming teeth at
- 5 the outer periphery of said enlarged head for engaging insulating material concentrically disposed upon said shank and adjacent opposite sides of the walls of said casing whereby said terminal posts may be rigidly 15 secured in position by engaging said enlarged head against said insulating material.

DAVID H. MOSS.
